UNITED STATES PATENT OFFICE.

ELIAS JONES, OF INDIANAPOLIS, INDIANA.

CUSHION-HEEL.

1,113,645.

Specification of Letters Patent.

Patented Oct. 13, 1914.

Application filed May 1, 1913. Serial No. 764,873.

To all whom it may concern:

Be it known that I, ELIAS JONES, a citizen of the United States, and a resident of Indianapolis, county of Marion, and 5 State of Indiana, have invented a certain new and useful Cushion-Heel; and I do hereby declare that the following is a full, clear, and exact description thereof, reference being had to the accompanying drawings, in which like letters refer to like parts.

The object of this invention is to provide an improved construction of heels for shoes, boots and slippers, whereby the heel is rendered yielding or cushioned and yet the 15 lower and wearing portion of the heel is formed of leather like an ordinary shoe heel, and also the upper portion of the heel is formed of leather whereby it is secured to the sole of the shoe in the usual manner. 20 The chief feature of the invention consists in interposing one or more layers of rubber or like yielding material between the upper and lower layers of leather. In addition to the foregoing is the provision of 25 an air tight chamber within the heel which lies partially in the rubber layer and partially in the upper leather layer.

The recess above referred to forms an air cushion and the rubber layer forms a rubber cushion so that there is secured in this 30 heel the combined results flowing from the air cushion and the rubber cushion.

The nature of the invention will be understood from the accompanying drawings 35 and the following description and claim.

In the drawings, Figure 1 is a perspective view of the heel in complete form. Fig. 2 is a transverse section on the line 2—2 of Fig. 1. Fig. 3 is a longitudinal section on 40 the line 3—3 of Fig. 1. Fig. 4 is a perspective view of the heel.

A central layer of rubber 10 is provided which is relatively thick as compared with 45 the layers of leather 11, 12, 13 and 14 associated with the rubber layer. The rubber layer is provided with a central recess 15 which extends down through a little more than half of its thickness.

Upon the upper surface of the rubber 50 layer a leather layer 10 is secured and it is similarly recessed, so that the recess 15 is

formed in said layers 10 and 11. Upon the layer 11 of the leather a top layer 12 of leather is secured. The top layer 12 covers and closes the air chamber 15. The layers 55 are preferably secured together by glue, or, if desired, the leather and rubber layers may be vulcanized together, so that the chamber 15 will be air tight.

After the layers are secured together in 60 the manner explained, the heel is secured to the sole of the shoe by tacks, pegs or other usual means, which penetrate the leather layers 11 and 12 and surround but do not penetrate the air chamber 15. The lower 65 layers 13 and 14 of leather furnish a leather tread for the shoe which causes the heel to wear a long time and gives to it the same sound while walking that is given by the ordinary leather heel. This heel construction avoids the silent or gum heel tread sound so objectionable in heels provided with rubber on the bottom thereof. Therefore, applicant has a combined air and rubber cushioned heel, wherein the air in the 70 chamber 15 yieldingly resists pressure, and likewise the rubber yields to the tread. 75 This gives a comfortable feeling to the user and has all of the virtues of the rubber heel with the additional advantage arising from 80 the air cushion and also avoids the objections of the usual rubber heel in the matter of sound thereof while walking. After the heel is put in place, it may be trimmed in the usual manner and when trimmed and 85 colored, it is substantially the same in appearance as an ordinary leather heel, the rubber not appearing essentially different from the leather and this presentable appearance remains during the wear of the 90 heel for the wear does not come on the rubber. Another advantage of this construction is that the heel can be repaired without 95 injuring the rubber. For if the lower layer of leather has worn, it can be replaced just as ordinary leather heels are replaced and without disturbing the layer of rubber and the air cushion.

The invention is:

A heel for shoes and the like including 100 a layer of rubber with a recess centrally located in the upper part thereof, a layer

of leather secured upon said layer of rubber and correspondingly recessed, another flat imperforate layer of leather secured upon said recessed layer of leather and closing said recess to form an air tight chamber, and a layer of leather forming the tread portion of the heel.

In witness whereof, I have hereunto affixed my signature in the presence of the witnesses herein named.

ELIAS JONES.
